(57) **CLAIM**

The ornamental design for a hand dryer, as shown and described.

DESCRIPTION

FIG. 1 is a perspective view of a hand dryer;

FIG. 2 is an alternative perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

In the drawings, the surface finish of the hand dryer may be smooth/gloss, satin, brushed, or otherwise textured. No claim is made to texture or surface finish. Any broken lines (e.g., dash lines, dot lines, dash-dot-dash-dot lines) in the drawings illustrate portions of the hand dryer that form no part of the claimed design.
